(57) **CLAIM**

The ornamental design for a pair of saddle bag support structures, as shown and described.

DESCRIPTION

FIG. 1 is a front view of a pair of saddle bag support structures showing my new design;

FIG. 2 is a rear view thereof;

FIG. 3 is a top view thereof;

FIG. 4 is a bottom view thereof;

FIG. 5 is a left view thereof;

FIG. 6 is a right view thereof;

FIG. 7 is an isometric front view of my instant invention on a reduced scale mounted on a motorcycle with its flap assembly in an open position;

FIG. 8 is an isometric front view of my instant invention on a reduced scale mounted on a motorcycle with its flap assembly in a closed position; and,

FIG. 9 is an isometric front view of my instant invention on a reduced scale mounted on a motorcycle and supporting a saddle bag flap.

The broken lines are for environmental purposes only and form no part of the claimed design.

The claimed design is directed to a pair of saddle bag support structures. The saddle bag support structure shown on the left side of the motorcycle in FIG. 9 is a mirror image of the saddle bag support structure shown and described in FIGS. 1-8, and is not shown in FIG. 1-8 for clarity of illustration.
